UNITED STATES PATENT OFFICE.

CHARLES C. GUERNSEY, OF NASHVILLE, TENNESSEE, ASSIGNOR, BY DIRECT AND MESNE ASSIGNMENTS, TO AMERICAN NON-REFILLABLE BOTTLE COMPANY, A CORPORATION OF MAINE.

NON-REFILLABLE BOTTLE.

SPECIFICATION forming part of Letters Patent No. 741,578, dated October 13, 1903.

Application filed November 28, 1902. Serial No. 133,050. (No model.)

To all whom it may concern:

Be it known that I, CHARLES C. GUERNSEY, a citizen of the United States, residing at Nashville, in the county of Davidson and State of Tennessee, have invented certain new and useful Improvements in Non-Refillable Bottles, of which the following is a specification.

This invention is designed to provide a bottle or like receptacle embodying a novel combination and assemblance of parts whereby protection is afforded the producer of certain vendible commodities against the fraudulent reuse of his bottle and consequent deceiving of the purchasing public.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a vertical central section of the upper portion of a bottle embodying the invention, showing the guard, valve, and weight in full. Fig. 2 is a view similar to Fig. 1, showing the bottle turned to pour off the liquid contents. Fig. 3 is a perspective view of the guard. Fig. 4 is a horizontal section of the guard on the line X X of Fig. 3.

Corresponding and like parts are referred to in the following description and indicated in all the views of the drawings by the same reference characters.

In carrying out the invention the bottle-neck 1 is formed with an integral valve-seat 2 at approximately the point of juncture with the body 3 of the receptacle. The above may be done during the process of manufacture of the bottles in a manner with which all versed in the art to which the same appertains are cognizant. In the operation above premised upon an annular groove 4 is also formed upon the inner side of the neck and about at the mouth thereof, said groove co-operating with means hereinafter to be de-

scribed to hold a guard of peculiar construction in position.

A float-valve 5 of any form found desirable is seated in the valve-seat 2 of the bottle-neck, being retained normally in such position by a pendent weight 6, connected thereto by preferably a flexible connection 7. The weight 6 is located within the body of the bottle and permits a limited movement of the valve 5 in the neck 1. It will be understood that the form of the valve 5 is unessential except that it is of the float type and may be a hollow glass ball or cork float or other structure of like nature and answering the requisite purposes.

Above the float-valve 5 is rigidly disposed within the neck a guard 8, said guard having also an annular groove 9, corresponding to the groove 4 in the bottle-neck, disposed upon the outer side at the upper portion thereof. A locking-spring 10 is used to lock the guard 8 in the neck against removal. Cement or other means, however, may be used to perform this latter function. Vertical passages 11, the number of which will depend upon the size and general purpose for which the article is utilized, extend at right angles to the groove 9 of the guard to the lower end of same. Lateral ducts 12 extend from the upper end of the passages 11, and downwardly-inclined openings 13 lead from the said ducts through the sides of the guard into a recess 14, formed in the latter. The bottom of the recess 14 is closed, as shown most clearly in the drawings. The upper end of the guard is also flanged, (see 15,) so as to overlap the sides of the bottle-mouth, this affording a more secure locking of the said guard. The openings 13 are inclined toward the bottom of the recess 14 to prevent the insertion of a wire or other implement to counteract the proper operation of the valve in the attempt to practice fraud.

In the adaptation of the device in use the bottle is first filled in the usual manner with the desired contents. The float-valve 5, with its pendent weight, is next introduced, the weight first, the same entering the body of the bottle and passing beyond the valve-seat. The guard is now placed in position and is

permanently locked in the neck in the manner before described. To empty the contents of the bottle, the same is inverted, and the weight 6 releasing the valve the same floats, 5 allowing the contents to pass below the valve, through the passages 11, lateral ducts 12, and openings 13 into the recess 14 of the guard and out of the receptacle. If an attempt is 10 made to refill the bottle when the same is inverted, the introduction of the contents causes the float 5 to seat itself, owing to its buoyant qualities, and of course this immediately thwarts the device. It will be apparent that 15 such an attempt is impossible of accomplishment when the bottle is in an upright position, the weight then holding it rigidly seated.

A cork 16 is used to close the open end of the recess 14 to seal the bottle in the common manner.

20 Having thus described the invention, what is claimed as new is—

1. In a bottle, a guard to be secured in the neck of the bottle and having a recess in its upper end, an annular groove in the outer 25 side near its upper end, vertical passages connected at their upper ends with said annular groove and extending through the lower end

of the guard, lateral passages in communication with said annular groove and the respective vertical passages, and having openings 30 connecting the lateral passages with the aforesaid recess, substantially as specified.

2. In combination, a bottle having a neck provided at its inner end with a counterbalanced float-valve, and near its outer end with 35 an inner annular groove, a guard secured within the outer end of said neck and having a recess in its upper end, an annular groove in the outer side near its upper end, vertical passages connected at their upper ends with 40 said annular groove and extending through the lower end of the guard, lateral passages in communication with said annular groove and the respective vertical passages, and having inwardly and downwardly inclined openings 45 connecting the lateral passages with the aforementioned recess, substantially as set forth.

In testimony whereof I affix my signature in presence of two witnesses.

CHARLES C. GUERNSEY. [L. S.]
